(57) **CLAIM**

The ornamental design for a multiple electric socket, as shown and described.

DESCRIPTION

FIG. 1 is an exploded top perspective view of an embodiment of a multiple electric socket showing my new design;

FIG. 2 is a second embodiment of a multiple electric socket showing my new design;

FIG. 3 is an exploded top perspective view thereof;

FIG. 4 is a bottom plan view thereof;

FIG. 5 is a side elevation view thereof;

FIG. 6 is a top plan view thereof; and,

FIG. 7 is a side elevation view thereof, with the top portion removed for ease of illustration.

The broken lines shown represent unclaimed subject matter and form no part of the claimed design.
